CLAIM

The ornamental design for a fire pit, as shown and described.

DESCRIPTION

FIG. 1 is a top, front, right-side perspective view of a fire pit;
FIG. 2 is a bottom, back, left-side perspective view thereof;
FIG. 3 is a front view thereof;
FIG. 4 is a back view thereof;
FIG. 5 is a left-side view thereof;
FIG. 6 is a right-side view thereof;
FIG. 7 is a top view thereof; and,
FIG. 8 is a bottom view thereof.
The dashed broken lines depict portions of the fire pit that
form no part of the claimed design.
